UNITED STATES PATENT OFFICE.

ROBERT H. MILLER, OF DETROIT, MICHIGAN, ASSIGNOR TO DETROIT STOVE WORKS, OF DETROIT, MICHIGAN, A CORPORATION OF MICHIGAN.

STOVE CONSTRUCTION.

1,305,394.

Specification of Letters Patent. Patented June 3, 1919.

Application filed May 12, 1917. Serial No. 168,154.

To all whom it may concern:

Be it known that I, ROBERT H. MILLER, a citizen of the United States of America, residing at Detroit, in the county of Wayne 5 and State of Michigan, have invented certain new and useful Improvements in Stove Constructions, of which the following is a specification, reference being had therein to the accompanying drawings.

10 This invention relates to stove constructions such as electric ranges or the like.

The invention generally resides in the various features of construction and arrangement of parts.

15 Among the objects of the invention are to provide a construction in which the insulated walls are built up of blocks or the like which can be readily assembled; to provide an improved arrangement for the 20 electrical connections to the ovens; to prevent any grease or other substance from injuring the switch terminals; and in general to provide a new and improved stove construction or electric range.

25 In the drawings:

Figure 1 is a rear view of an electric range embodying my invention;

Fig. 2 is a horizontal section on the line 2-2 of Fig. 1;

30 Fig. 3 is a vertical section on the line 3-3 of Fig. 1;

Fig. 4 is an enlarged vertical section through one of the top plates of the stove;

Fig. 5 is a vertical sectional view through 35 the oven;

Fig. 6 is a view similar to Fig. 5 taken at right angles thereto.

In detail A designates an electric range which, as shown in the drawings, is of the 40 high oven type having adjacent the open burner section B a pair of ovens, such as the main oven C and the broiler oven D. Suitable resistance or heating units E and E' are mounted in the ovens C and D and 45 also suitable heating units F for the top plates F'.

Heretofore in the construction of ovens or electric stoves it has been usual to fill in the space between the walls G and G' 50 with an insulating material packed into the space between these walls.

The present invention contemplates an improved arrangement whereby the insulating space between the various walls G 55 and G' is built up with insulator blocks H.

These blocks are formed of insulating material molded or otherwise formed into the proper shape. The various blocks have lap-joints J so that in assembling the parts they will avoid the formation of air spaces, this 60 arrangement further facilitating the assembling of the insulating lining in the stove.

At the rear of the ovens the resistance elements E and E' are provided with terminal blocks K and K'. In the novel construction shown in the drawings these blocks are located in a chamber formed by a vent pipe or conduit L. As shown in Fig. 1 this conduit at its lower end has an offset portion L' through which the leading in wires M are conducted to the terminal blocks K and K', the lower end of the vent pipe L being also used as part of the chamber for the leading in wires. The connection between the broiler chamber D and the vent pipe or chamber L is through one or more baffle plates or chambers N and N' so that the gases passing through the openings O are compelled to baffle in the chambers N and N' before passing out through the openings O' in the rear wall. It will be noticed that the openings O' are so located that the gases passing to the vent are compelled to pass over the terminal blocks 85 K and K', thus tending to prevent any excessive heating of the latter.

The connection to the vent pipe from the oven C is through a port or ports Q and out through the pipe connection Q'.

90 The invention also resides in the improved arrangement whereby injury to the switch blocks R is prevented. As shown in Fig. 4 the switch blocks are located at the front of the stove and in order to prevent any grease 95 or other material passing down from the hot plate and injuring the terminal connections, the latter are mounted in a recess member S having at its upper end a sloping flange S' terminating in a trough or conduit T by 100 means of which any substance leaking through from the hot plate is conducted down to the drip pan T'. At the lower end the housing S is formed with a supplemental housing V in which the usual fuse block 105 plug V' is located. This plug is accessible through a door V'.

From the above description it will be apparent that the construction is one which can be economically manufactured and in 110

which all the parts while protected from injury are accessible.

What I claim as my invention is:

1. In an electric range, the combination 5 with a cooking top and an oven, of electrical resistance for the oven, leading in wires from the cooking top portion of the stove to said electrical resistance, and an air vent for the oven also forming a housing for said 10 leading in wires, said air vent having a lateral offset portion extending beyond the plane of the oven.

2. In an electric range, the combination of superposed ovens, of resistances therefor, 15 electrical connections for said resistances, an air vent secured to said stove and also forming a housing for said electrical connections, and ports connecting said ovens with said air vent.

20 3. In an electric stove, the combination with a hot plate, of a switch located beneath said hot plate, and a protective casing for said switch having an inclined top and a trough or conduit at the lower edge of 25 said top for conducting away any injurious substances passing down through the hot plate.

4. In an electric range, the combination with an oven, of a heating resistor therein, 30 an electrical connection for said resistor, an

air vent secured to said oven and also forming a housing for said electrical connection, and a port connecting said oven with said air vent.

5. In an electric range, the combination 35 with superposed ovens, of heating resistors therefor, electrical connections for said resistors, an air vent secured to said oven forming a housing for said electrical connections, ports connecting said ovens with 40 said air vent, and baffle chambers in one of said ovens into which said ports open.

6. In an electric range, the combination with an oven, of a heating resistor there- 45 within, electrical connections for said resistor, terminal blocks for said electrical connections, and an air vent secured to the oven and forming a housing for said elec- 50 trical connections and terminal blocks, the opening from the oven into the air vent being located adjacent the terminal block to compel a passage of air adjacent the terminal block to cool the same.

In testimony whereof I affix my signature in presence of two witnesses.

ROBERT H. MILLER.
